United States Patent Office

Des. 195,721
Patented July 23, 1963

195,721

DUMP TRAILER

Francis K. Quinn, 3420 Sweet Drive, Lafayette, Calif.

Filed Jan. 31, 1962, Ser. No. 68,585

Term of patent 14 years

(Cl. D14—3)

Fig. 1.

Fig. 2.

Fig. 3.

FIG. 1 is a view in side elevation of a dump trailer showing my new design;

FIG. 2 is a top plan view of the same;

FIG. 3 is a view in front elevation of the same.

The side not shown is a mirror image of the side shown.

I claim:

The ornamental design for a dump trailer, substantially as shown and described.
